UNITED STATES PATENT OFFICE

117,627

DESIGN FOR A WASHING MACHINE CABINET

Hyman D. Brotman, Detroit, Mich.

Application September 30, 1939, Serial No. 87,446

Term of patent 14 years

To all whom it may concern:

Be it known that I, Hyman D. Brotman, a citizen of the United States, residing at Detroit, in the county of Wayne and State of Michigan, have invented a new, original, and ornamental Design for Washing Machine Cabinets, of which the following is a specification, reference being had to the accompanying drawings, forming part thereof.

Figure 1 is a front elevational view of the washing machine cabinet, showing my new design;

Fig. 2 is a side elevational view of Fig. 1;

Fig. 3 is a perspective view including the front and side view as shown in Figs. 1 and 2;

Fig. 4 is a detailed front elevational view, on

an enlarged scale, of the escutcheon plate which forms part of the design shown in Figs. 1, 2, and 3.

Fig. 5 is a vertical sectional view of the body of the plate taken on line 5—5 of Fig. 4;

Fig. 6 is a vertical sectional view through the wing of the plate taken on line 6—6 of Fig. 4, and

Fig. 7 is a horizontal sectional view of the body of the plate taken on line 7—7 of Fig. 4.

I claim:

The ornamental design for a washing machine cabinet, as shown.

HYMAN D. BROTMAN.
